APPARATUS FOR COATING ELONGATED ARTICLES

George Mason and John B. Mason, Kansas City, Mo., and Arie M. Mason and Benjamin Mason, Prairie Village, Kans., assignors to Mason Plastics Co., Inc., Kansas City, Kans., a corporation of Kansas

Application December 8, 1952, Serial No. 324,731

5 Claims. (Cl. 118—404)

This invention relates to apparatus for coating various types of articles, particularly those of an elongated nature, with substances that are initially in at least a semi-fluid condition and capable of drying and hardening when exposed to the atmosphere.

It has been found advantageous with respect to many articles of merchandise to place protective coatings thereon, and in the use of the particular invention herein involved, such coating substance takes the form of a synthetic plastic material. Such materials, when properly formulated, are capable of rendering the article coated thereby waterproof, resistant to excessive wear, and electrically insulated.

One of such articles includes electrical probes in the nature of elongated poles, it being highly essential that such probes be insulated against passage of electrical currents. The probes are usually made of wooden stock and unless the same are kept in a dry condition at all times, they become extremely dangerous when working with high tension lines. Furthermore, while the wood poles are light and inexpensive and therefore, 35 advantageous from this standpoint, they are not long-lasting because of the abuse that the same must take during use. A much more efficient article is thereby presented through coating of the same with a plastic substance as above mentioned, and it is the primary object of the present invention therefore, to present apparatus that will render such task easy and efficient.

The most important object of the present invention is to provide coating apparatus that includes a housing for the coating substance having a die assembly for receiving the article to be coated, together with a novel valve that may be closed to permit changing of the die assembly as needed to accommodate articles of differing diameters.

Another important object of the present invention is the provision of a die assembly that is mounted within the valve and accordingly, within the housing for containing the coating materials, through novel structure that facilitates easy and rapid changing as desired.

Another object of this invention is to provide in apparatus for coating elongated articles, structure for advancing the article to be coated and simultaneously rotating the same on its longitudinal axis.

Other objects include the way in which the article-advancing means includes a pair of angularly displaced rollers that are individually driven and engage the article itself; the way in which the rollers are mounted on swingable arms that include structure for varying the distance between the rollers as desired; and many more minor objects including details of construction, all of which will be made clear or become apparent as the following specification progresses, reference being had to the accompanying drawing, wherein:

Figure 1 is a front perspective view of apparatus for coating elongated articles made pursuant to the present invention.

Fig. 2 is an enlarged, fragmentary, front elevational

2

view illustrating the article advancing mechanism together with the die housing.

Fig. 3 is an enlarged, fragmentary, cross-sectional view taken on irregular line III—III of Fig. 2.

Fig. 4 is a cross-sectional view taken on line IV—IV of Fig. 3; and

Fig. 5 is a cross-sectional view taken on line V—V of Fig. 4.

The elongated rod or pole 10 to be coated through use of the apparatus about to be described, is illustrated in Fig. 1 of the drawings. While, as above mentioned, the pole 10 is adapted for use in connection with high tension electrical wires, it may well have other advantageous uses after coating thereof and articles differing from that illustrated may also be coated when the present machine is placed in operation.

The pole 10 is advanced through a die housing broadly designated by the numeral 12 and simultaneously rotated on its longitudinal axis through means of mechanism 14, the construction and operation whereof will hereinafter be set forth. The substance that is used to coat the pole 10 is contained or stored within an elevated tank 16 that terminates at its lowermost end in a hopper-like portion 18, all of which is in turn supported by framework or leg means 20. The hollow housing 12 is mounted directly upon the normally front face of the tank 16 and is of double-wall construction as illustrated in Figs. 3, 4 and 5 to present a hot water chamber 22 that substantially surrounds a compartment 24 for receiving the coating substance from the tank 16. Tank 16 is also substantially of double wall construction throughout as shown in Figs. 3 and 5, to present a space 26 that also receives hot water.

A liquid pump 28 communicates at its outlet end with a heater 30 which in turn is joined with the chamber 22 at its uppermost end by a line 32. A pipe 34 interconnects the chamber 22 of housing 12 with the space 26 of tank 16 and space 26 is in turn joined with the inlet of pump 28 by means of a pipe 36 shown in part only in Fig. 1 of the drawings.

The compartment 24 of housing 12 is in direct communication with the hopper portion 18 of tank 16 by means of an opening 38; and a valve assembly or gate means broadly designated by the numeral 40, is mounted within the compartment 24. Valving means 40 includes a hollow cylinder 42 that is rigidly secured to the housing 12 therewithin and provided with a plurality of spaced, circumferentially arranged, elongated slots or openings 44. A cylindrical band 50 circumscribes the cylinder 42 and is rotatably mounted thereon. The band 50 is likewise provided with a number of elongated slots or openings 52. Rotation of the band 50 to bring the openings 52 thereof in and out of register with openings 44, is accomplished through the medium of an arm 62 that is secured directly to the band 50 and extends laterally therefrom.

A crank 59 having a slot 61 for receiving pin 63 on arm 62 is pivotally connected with a link 64 by means of a rod 65. A handle 66 exteriorly of the tank 16 and swingably secured thereto joins with the link 64.

A combination die assembly and flow control means 46 in valve 40 includes a pair of perforated end discs 47 and 48 carried by housing 12 and interconnected by a number of rods 49. An inlet tube 51 is mounted on disc 47, and disc 48 has a frusto-conical bore portion 53 adapted to receive a tubular member 54. A band 55 on member 54 is slidable on the rods 49 and has a setscrew 56 for holding the same in adjusted positions. Tube 51 and member 54 are internally bevelled at the inlet ends thereof as at 57 and 58 respectively to facilitate insertion of member 10, and member 54 is exteriorly bevelled at the opposite end thereof as at 60. Member 54 is of

resilient material and provided with a number of longitudinal slots 68.

A cavity 70 in disc 48 receives a wiping washer 72 that is in turn held in place by a removable, perforated end plate 74, on housing 12. A second end plate 76 surrounds tube 51.

Optional equipment for assuring fast drying of the coating on the pole 10, includes an annular, hollow member 78 held in circumscribing relationship to the article 10 by means of a laterally extending arm 80. A bracket 82 on the housing 12 releasably receives the arm 80. Member 78 is provided with a plurality of extremely fine perforations 84 on its innermost face for the escape of air under pressure that is directed to the member 78 by means of a tube 51.

Mechanism 14 includes a suitable stand 88 having a lowermost pair of spaced arms 90 swingably secured thereto by means of a shaft 92. Likewise, an uppermost pair of spaced-apart arms 94 is swingable relative to the frame or support 88 by means of a horizontal shaft 96 directly above and substantially parallel with the shaft 92.

Arms 90 and 94 rotatably mount rollers 98 and 100 respectively, each of which is longitudinally concave and mounted on horizontal shafts 102 and 104 respectively. Shafts 102 and 104 are in separate vertical planes that intersect each other and the longitudinal axis of article 10 as is clear in Figs. 1 and 2 of the drawings.

Rotation is imparted to the rollers 98 and 100 through the medium of an electric motor or other prime mover 106, operably coupled with a shaft 108 through speed reducer 110. A pulley 112 on shaft 108 is operably joined with the speed reducer 110 through a continuous belt 114 and shaft 108 is provided with another pulley not shown, over which a continuous belt 116 is trained. Belt 116 also passes over a pulley 118 to impart rotation to shaft 96 and a second pulley on shaft 96 not shown, joined with a pulley 120 on shaft 104 through the medium of a belt 122.

A gear box 124 is provided with a pair of intermeshing gears not illustrated, having a 1 to 1 ratio. One of the gears is joined to shaft 108 while the other gear is on a stub shaft 126 having a pulley 128 thereon. Shaft 92 has a pair of pulleys 130 and 132, the former of which is connected with the pulley 128 by continuous belt 134. Pulley 132 is joined with a pulley 136 by continuous belt 138, pulley 136 being secured directly to shaft 102.

It is seen that through such coupling of the rollers 98 and 100 with the prime mover 106, rollers 98 and 100 are driven in a direction to impart advancement to the rod 10 as well as rotation on its longitudinal axis. The rollers 98 and 100 are held in tight engagement with the article 10 by means of an adjustable clamping assembly 140, that includes bars 142 and 144 rigid to arms 90 and 94 respectively.

A pair of interconnected rods 146 are threaded through the bars 142 and 144 at each end respectively thereof and a cross-head 148 overlying the bar 144, slidably receives the uppermost rods 146. Adjustment is attained in part by means of nuts 150 on the ends of the rods 146. A tubular adjusting screw 152 carried by the cross-head 148, receives a reciprocable bolt 154 that passes downwardly through cross-head 148 and through the bar 144, there being an adjusting nut (not shown) on the lowermost end of the bolt 154 below the bar 144. A spring 156 is interposed between cross-head 148 and the bar 144 in coiled relationship to the bolt 154. Bolt 154 has a cross-pin 158 at the uppermost end thereof for swingably and eccentrically receiving a cam member 160 provided with a handle 162. It is seen that when the handle 162 is swung downwardly on the bolt 154 to one end of its path of travel, the spring 156 is compressed as bar 144 moves toward the cross-head 148, thereby releasing the rollers 98 and 100 relative to the article 10. When the handle 162 is swung upwardly to the opposite end of its path of travel, spring 156 oper-

ates to separate bar 144 and cross-head 148, thereby yieldably holding the rollers 98 and 100 in engagement with the article 10. The distance between the rollers 98 and 100 when the same are operably engaging the article 10, may be varied by adjusting screw 152, nuts 150, or the nut on the lowermost end of the bolt 154. A counterweight 164 on the uppermost arms 94, serves to maintain the article 10 properly centered with respect to the tube 51 and the die assembly 46.

10 A carriage 166 is provided with rollers 168 that ride on the uppermost edge of an elongated track 170. Carriage 166 is also provided with a lowermost roller 172 that engages one vertical face of a relatively long bar 174. Carriage 166 has a bracket 176 that pivotally carries a lateral extension 178 having a notched plate 180 secured thereto. A nail or like element 182 driven into one end of the article 10 is received by the notch or plate 180. A yieldable bias is placed on the extension 178 by means of a spring 184 that holds the extension 178 against the carriage 166 as determined by an adjustable stop 186.

15 An instrument panel 188 is provided to receive the various necessary controls for prime mover 106, an electric motor 190 for pump 28, a valve to control the flow of air to member 78, certain electric switches, as well as temperature and pressure gauges as illustrated.

20 It is seen that in operation, article 10 is threaded between the rollers 98 and 100 when the same are released through use of handle 162 and when rollers 98 and 100 are caused to rotate by energization of prime mover

25 106, the article 10 will be projected through the member 54 and simultaneously rotated on its longitudinal axis. With valve 40 open, the plastic coating substance is free to flow from the tank 16 through hopper portion 18 to the compartment 24 by way of opening 38. Such substance enters the cylinder 42 by means of aligned openings 44 and 52 and also enters the bore portion 53. As the article 10 is advanced, it will become coated with the substance and cleared of excess material by the wiping washer 72. Element 182 is thereupon placed in the plate 180 and the carriage 166 caused to move along the tracks 170 and 174 by the advancement of the article 10. While the article 10 is supported by the carriage 166, spring 184 provides for the necessary yielding so as to prevent any possibility of jamming or binding 30 within the housing 12.

35 The coating substance is maintained at a predetermined temperature so as to remain semi-fluid through hot water emanating from heater 30 and passing first to the chamber 22 and thence to the space 26 for return to pump 28 by means of pipe 36. If desired, the coating substance may be dried more rapidly by use of the member 78 since air under pressure emanating from the minute perforations 84 will impinge directly upon such substance as soon as the same emerges from the housing 12.

40 When it becomes necessary to change the assembly 46 to accommodate articles 10 of differing diameters, it is but necessary to remove the plates 74 and 76. In order to prevent flow of the coating substance from the compartment 24, the operator need merely manipulate handle 66 to rotate band 50 and thereby close the openings 52 relative to openings 44.

45 While my method for coating elongated articles, fully disclosed and claimed in our co-pending application, Serial No. 324,732, filed December 8, 1952, and entitled—"Method of Coating Elongated Articles"—forms no part of the present invention, it may be pointed out by way of explanation that the amount of plastic substance that is permitted to flow to the rod or pole as the latter is within bore 53 and approaching wiping washer 72 is extremely important. Such flow may be precisely controlled by the shifting of the member 54 along the longitudinal axes of the rods 49. The operator need merely loosen the setscrew 56 and project the bevelled 50 end 60 of the member 54 further into the disc 48, i. e., the

frusto-conical bore portion 53 thereof, to diminish the rapidity of flow of the substance from within the valving means 40 into the bore 53 of the disc 43. The bevelled portion 60 cooperates with the bore portion 53 in facilitating uninterrupted flow of the material, but the amount of the substance that is deposited upon the pole 10 as the same moves spirally through the housing 12, is dependent entirely upon the amount of said substance within the bore 53 of the disc 43. The material is immediately wiped by the circular washer 72 to assure an even coating of the substance on the pole 10. In the method aforesaid, a rather thin coating of the substance is placed on the pole 10 during its first passage through the housing 12.

After drying a predetermined period of time, the pole may thereupon again be extended through the housing 12, but before the next operation, the plate 74 is removed and a wiping washer 72 of slightly larger internal diameter is inserted in the cavity 70. Likewise, in subsequent coating operations, washers 72 of progressively increased inside diameters are substituted. It is apparent also that if desired the operator can quickly and easily adjust the member 54 between the operations. Each time the plate 74 is removed, valve 40 may be closed to avoid loss of the material from the housing 12.

Some of the particular substances that may be used in the apparatus hereof consist of such synthesized materials as "hyper-solids gel," organosols, and plastisols. Such materials are capable of gelatinating solely by changing of their temperatures which may include a solvent that evaporates during the setting thereof on the pole, together with a suitable film forming media or ester. A plasticizer and a coloring pigment may be used if desired.

The machine hereof takes advantage of these characteristics of the gelatinous materials, causing the same to form on a regular-shaped object by use of the member 54 and the sizing die 72. Noteworthy is the fact that the article 10 enters the controlled flow composition below the surface thereof, making possible a continuous process, eliminating all problems of picking up "skins" on such surface.

Use of spring or mechanically centered member 54 presents the object 10 in proper relation to the sizing means 72 and should be positioned as close as practical thereto while assuring smooth, continuous and sufficient flow of the substance to the pole 10. By use of ring 78, air blasts may be directed to the coated member to break up air bubbles and present a smooth finished surface.

Other important factors relating to critical steps that must be followed have to do with the method as aforesaid and need not be enumerated herein for a full understanding of the operation of the apparatus above set forth.

Having thus described the invention what is claimed as new and desired to be secured by Letters Patent is:

1. In article coating apparatus, a hollow housing adapted to contain a coating substance; a hollow cylinder mounted within the housing; a tubular member adapted to receive an article to be coated and traversing the housing and the cylinder, said member communicating with the cylinder; and a band circumscribing the cylinder for rotation relative thereto, said band and said cylinder having inlet openings formed therein and disposed for registration upon rotation of the band to admit said coating substance to the cylinder; means including one end of said member for limiting the flow of said substance between said end of the member and a portion of said housing and onto the article as the latter is moved from said end of the member; and means carried by the housing for limiting the thickness of the coating of said substance on the article.

2. In a coating machine, a container for a coating substance having an inlet opening and an outlet opening for receiving an article to be advanced through the substance; sizing means adjacent the outlet for controlling the thickness of a coat of said substance on the article; means with-

in said substance for guiding the article through the sizing means and thereby render said coat of uniform thickness; means including a disc having an opening therethrough disposed to cooperate with one end of the guide means for limiting the extent of flow of said substance between said disc and said guide means and onto the article; and gate means surrounding the guide means and the flow limiting means for controlling the flow of said substance thereto.

3. In a coating machine, a container for a coating substance having an inlet opening and an outlet opening for receiving an article to be advanced through the substance; sizing means adjacent the outlet for controlling the thickness of a coat of said substance on the article; means within said substance for guiding the article through the sizing means and thereby render said coat of uniform thickness; means including a disc having an opening therethrough disposed to cooperate with one end of the guide means for limiting the extent of flow of said substance between said disc and said guiding means and onto the article, said guide means being movable toward and away from said flow limiting means whereby to vary said flow; and gate means surrounding the guide means and the flow limiting means for controlling the flow of said substance thereto.

4. In a coating machine, a container for a coating substance having an inlet opening and an outlet opening for receiving an article to be advanced through the substance; sizing means adjacent the outlet for controlling the thickness of a coat of said substance on the article; resilient, article-engaging means disposed within said substance for centering and guiding the article through the sizing means to thereby render said coat of predetermined and uniform thickness; means including a disc having an opening therethrough disposed to cooperate with one end of the guide means for limiting the extent of flow of said substance between said disc and said guide means and onto the article, said guide means being movable toward and away from said flow limiting means whereby to vary said flow; and gate means surrounding the guide means and the flow limiting means for controlling the flow of said substance thereto.

5. A coating apparatus comprising, a jacketed container for the coating composition and adapted to receive a predetermined quantity of same; means for heating said jacketed container, said container having two aligned apertures disposed below the level of said composition for passing the article to be coated; tubular means carried in one aperture for passing the article without leakage; wiping means carried in the other aperture for passing the article with a predetermined thickness of coating; and valve means extending from side to side of said container below the level of said composition for keeping the latter from said apertures, while changing the sizes of said first mentioned means carried in each of said apertures.
